UNITED STATES PATENT OFFICE

ROBERT BAUERLE, OF CHICAGO, ILLINOIS, ASSIGNOR, BY MESNE ASSIGNMENTS, TO KEWANEE MACHINERY & CONVEYOR CO., OF KEWANEE, ILLINOIS, A CORPORATION OF ILLINOIS

CAR LOADER

Application filed March 7, 1929, Serial No. 345,049. Renewed October 8, 1930.

My invention relates to car loading appliances in general and concerns more specifically structures for loading pit-cars of mines.

In the mining of coal, it is customary to deliver it into a stationary pit-car capable of travelling on suitable rails and the base or truck portion of the loading apparatus is designed to rest on the same rails and of course to travel thereon when moved from one location to another.

The main object and purpose of the present invention is to provide a loading appliance which, while bearing on such rails, can be shifted angularly in substantial measure so that the coal may be delivered into the car over a comparatively wide range of receiving points, the apparatus being so constructed that its position or angular disposition may be varied as occasion requires without substantial interference with the supporting pillars or posts in the general location where the loading is to occur.

To the attainment of this and other desirable objects, I have devised the novel invention, a present preferred embodiment of which is illustrated in the accompanying drawings, forming a part of this specification and throughout the several views of which like reference characters have been employed to designate the same parts.

In these drawings:—

Figure 1 is an elevation of the apparatus;

Figure 2 is a cross section through the same on a larger scale on line 2—2;

Figure 3 is a plan view of the structure; and

Figure 4 is a detailed view of the expandable and contractible trackway supporting the conveyor.

Referring to these drawings, it will be noted that the lower truck portion of the loader comprises a suitable truck-frame 11 equipped with flanged wheels 12, 12 adapted to bear and to travel on the same rails 13, 13 as accommodate the pit-car, not shown, whereby the appliance as a whole may be caused to travel on such rails, when it is desired to change its location, by means of an electric-motor 14 mounted on the truck-frame 11 and suitably operatively connected, as by a

sprocket-wheel and chain mechanism 15, to one of the truck axles, thus permitting the loader to move itself along the rails under its own power as occasion demands.

On the depressed truck-frame, between its pairs of wheels, there are fixedly mounted a pair of channel-bar tracks 16, 16 and beside each of these there is another companion, slideable, channel-bar track 17, the backs of the two channels being toward one another. 60

In order to join the two, supplemental, slideable tracks together to form a unit, they are connected together in any approved manner, as by a pair of smaller channel members 18, 18. 65

The main track elements 16, 16 are slightly higher than the auxiliary track members 17, 17, or they may be of the same depth with the former slightly elevated as by shims 20 employed beneath them, so that the upper faces 70 of the two sets will be a little different.

An auxiliary truck 19 having double-flanged carrying-wheels 21, 21 on the track members 16, 16, 17, 17 is adapted normally to be positioned directly over the center of the underlying or main truck 11, 12 as shown in Figure 2, and pivoted centrally on such upper truck at 22. I employ a suitable support 23 pivotally or hingedly carrying at its top 9 the framework, base and sloping sides 24 of 80 an endless conveyor comprising a pair of endless chains, 25, 25 and spaced cross-bars or slats 26, 26 connecting them together at intervals.

Such endless conveyor has a lower horizontal section 27 adapted to overlie the rails 13, 13, an inclined, intermediate portion 28 mounted directly on the support 23 and an upper horizontal part 29 designed to extend over the pit-car, whereby coal shovelled on to 90 the part 27 will be automatically carried up and discharged into the car by the upwardly moving slats of the conveyor, the latter being operated by an electric-motor and appropriate driving connecting means in a casing 31 on the underside of the conveyor frame.

When it is desired that the conveyor receive the coal from a position at one side of the trackway, as indicated in dotted lines in Figure 3, and to deliver it into the pit-car in 100

the same position as before, it is of course necessary to shift the receiving end of the conveyer to one side of the trackway but to retain its elevated discharge end over the trackway and the pit-car thereon.

5 This result is accomplished by manually pulling out the united, supplemental, channel rails 17, 17 in the proper direction, it being understood that they may be thus projected from either side of the truck-frame 11, and for the purpose of supporting their outer ends in their extended relation, each is supplied with a vertically-apertured bracket 32 which receives a transversely-perforated 10 pipe 33, the lower end of which is received in a hollow standard 34 designed to rest on the ground, demountable cross-pins 35, 36 accommodated in such holes supporting the pipe in the standard and supporting the 15 bracket on the pipe.

20 The crosswise-disposed, extension trackway having been thus properly positioned and sustained at its outer end, the auxiliary truck 19 carrying the conveyer is rolled out 25 on to the channels 17, 17, the conveyer mounting turning, as required, on the pivot pin 22.

25 If needed or desired, the inner movable rails 17, 17 may be held slidingly in position by means of clips 10, 10 fastened to the truck 30 frame and overlying their lower flanges.

35 The specified lateral projection of the telescoping trackway is readily accomplished without interference with neighboring or adjacent pillars or posts in the mine chamber, and when its use in this relation terminates, the auxiliary truck can be pushed back into 40 register with the main truck, the supports 33, 34 removed and the supplemental trackway slid back into original position.

45 From the foregoing it will be apparent that the endless conveyer may be turned to either 40 side of its supporting main truck in the manner indicated and easily and readily replaced in normal position, thus facilitating the filling of the pit-car by coal fed from different 45 locations on to the properly positioned lower end of the conveyer.

50 The invention is not limited and restricted to the precise and exact details of structure shown and described and these may be modified within comparatively wide limits without departure from the heart and essence of the invention and without the loss or sacrifice of any of its material benefits or advantages.

55 I claim:

60 1. In a car-loader, the combination of a main-truck equipped with carrying-wheels, a contractible and extensible trackway mounted on and crosswise of said main-truck, 65 an auxiliary-truck having carrying-wheels on said trackway, and a conveyer pivotally mounted on said auxiliary-truck, whereby the angular relation of said conveyer to said 65 main-truck may be varied by changing the

position of said auxiliary-truck on said trackway.

2. In a car-loader, the combination of a main-truck equipped with carrying-wheels, a telescopic contractible and extensible trackway mounted on said main-truck crosswise thereof, an auxiliary-truck having carrying-wheels on said track-way, an endless conveyer structure pivotally mounted on said auxiliary-truck, and means to support the outer 70 end of said trackway in its extended condition, whereby the angular relation of said conveyer to said main-truck may be varied by changing the position of said auxiliary-truck on said trackway.

75 In witness whereof I have hereunto set my hand.

80 ROBERT BAUERLE.
